UNITED STATES PATENT OFFICE.

DANIEL E. HENNESSY, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

WASHER SETTING.

Application filed October 12, 1922. Serial No. 594,099.

It is common practice to provide rubber heels with embedded washers adapted to permit passage of the nail therethrough but to block passage of the nail head to thereby serve as an anchor for the nail head and prevent the nail head from tearing through the heel. These washers are ordinarily placed upon pins fixed in the molds and held in position by these pins while the heel blank is softened and forced about the washers into the cavity. Placing the washers upon the pins requires a considerable period of time and accordingly causes considerable delay in the return of the mold to the press. My invention provides a method of placing the washers which obviates this delay and also possesses other advantages obvious to those skilled in the art. In the drawings accompanying this specification and forming a part thereof I have shown, for purposes of illustration, one form which my invention may assume. In these drawings:

Figure 1 represents a plate containing pins upon which the washers may be assembled.

Figure 2 shows a heel positioned on the pins, while

Figure 3 shows the heel carrying the washers.

Figure 4 shows in detail a washer receiving pin.

In the drawings I have shown a plate 11 adapted to be heated and provided with a plurality of pins 12 similar to the pins in a heel mold, each adapted to receive a washer 13, and recessed at 15 to provide a cavity beneath the washer 13. After the washers are all in position on the pins 12 the heel blank 14 is placed upon the pins in proper relation thereto and pressed into firm engagement with the washers 13 as shown in Figures 2 and 4 whereupon stock of the blank 14 is softened by the heat of the pins 12 and flows through the apertures of the washers 13 into the cavities 15 to form rivets 16 uniting the washers 12 to the blank 14. After this the blank 14 is removed from the pins 12 carrying with it, because of the adhesive surface of the heated blank 14 and because of the rivets 16, the washers 13. When the mold has been removed from the press and the cured heels removed from the mold the heel blanks 14 carrying the washers 13 are placed directly into the mold without

the customary delay for placing the washers on the mold pins and accordingly the mold is almost immediately returned to the press with a new charge.

Various details in the apparatus herein shown may be varied without departing from my invention and this disclosure is, in fact, illustrative only so that my invention is not limited thereto.

I claim:

1. The method of positioning washers on the washer pins of a mold prior to the molding operation which comprises pressing the washers in a heated condition against the rubber heel blank in proper positions to encircle the pins when the blank is thereafter placed in the mold cavity.

2. The method of inserting washers in a rubber heel which comprises securing the washers by the application of heat to the heel blank prior to the insertion of the latter in the mold and applying the blank to the mold cavity in such manner that the washers encircle the pins thereof.

3. The method of applying substantially flat washers to the surface of a heel blank prior to the inserting of the latter in the molds which comprises applying the washers to properly spaced heated pins and then applying the heel blank to said pins.

4. The method of applying washers to a rubber heel blank prior to its insertion in the mold which comprises softening the blank and forcing the washers in desired positional relation against the surface of the blank.

5. The method of applying washers to a rubber heel blank which comprises softening the blank by the application of heat, and forcing the washers in desired positional relation against the blank, prior to its insertion in the mold.

6. The method of securing washers in desired position in a rubber heel blank prior to its insertion in the mold which comprises positioning the washers on a heated support bringing the blank into contact with the so positioned washers and applying pressure sufficient to partially imbed the washers in the blank.

7. The method of securing apertured washers in desired position in a rubber heel blank prior to its insertion in the mold which comprises positioning the washers on a heated support, bringing the blank into

contact with the so positioned washers and applying pressure sufficient to force a portion of the rubber through the apertures of the washers.

5. The method of inserting a washer in a rubber heel which comprises, positioning the washer on a heated pin, bringing the heel in an unvulcanized position into contact with the so positioned washer, whereby the rubber at the point of contact is softened and the washer secured thereto, removing the heel and attached washer from the pin, and then molding and vulcanizing the heel.

9. That improvement in the process of manufacturing rubber heels having nail receiving washers embedded therein, which consists in securing the washers in a rubber heel blank in substantially the positional relationship which it is desired to have them bear to each other in the finished heel, by heating the blank at the points where the washers are applied, subsequently placing said blank in a heel mold, and then performing the molding and vulcanizing operations on the blank while holding said washers in said relationship.

10. That improvement in the process of manufacturing rubber heels having fastener receiving washers embedded therein, which consists in fixing the fastener receiving washers to the surface of a substantially unvulcanized rubber heel blank in substantially the positional relationship which it is desired to have them bear to each other in the finished heel, by softening the blank at the points where the washers are applied, and then molding said blank in the usual manner.

11. That improvement in the process of manufacturing rubber heels having fastener receiving washers embedded therein, which consists in fixing the fastener receiving washers to the surface of a substantially unvulcanized rubber heel blank in substantially the positional relationship which it is desired to have them bear to each other in the finished heel by the application of heat and then molding said blank in the usual manner.

In testimony whereof I have signed my name to the above specification.

DANIEL E. HENNESSY.
